MULTIPLE EXPANSION STEAM ENGINE

Herman G. Mueller, Erie, Pa., assignor, by mesne assignments, to Skinner Engine Co., Pittsburgh, Pa., a corporation of Pennsylvania

Application February 21, 1947, Serial No. 730,114

20 Claims. (Cl. 121—102)

1

This invention relates generally to multi-cylinder vertical compound steam engines using a "Woolf steam cycle," and it relates more particularly to steeple-compound, uniflow, poppet-valve, reversing stationary and marine steam engines, on which much higher steam temperatures can be used with resulting lower steam consumption.

The steam engines now in use, whether of the simple or multiple-expansion type, are generally limited to maximum steam temperatures of 600–650° F., because the walls and the piston rings of the cylinders, into which steam of these limited temperatures is admitted, cannot be satisfactorily lubricated with steam at higher temperatures. Also, in marine applications, the amount of cylinder oil which may be used is limited, due to the condition that this oil is carried in a highly emulsified condition by the exhaust steam to the surface condenser, where the steam is condensed to water—all of which is pumped back to the boilers for boiler feedwater. The contamination of this boiler feedwater with emulsified oil becomes a serious problem, since oil on the heating surfaces of the boiler, where it accumulates, causes serious trouble and overheating. Thus, marine steam engine cylinders have always been sparingly lubricated, and, in addition, steam temperatures have been quite limited and the trend has been to steam turbines, which require no internal lubrication, and can utilize higher steam temperatures.

Many compound triple- and quadruple-expansion marine steam engines are still in service, running with saturated or moderately superheated steam, and most of these engines have slide valves, and a few more modern engines have poppet valves with steam temperatures up to about 600° F. The fuel consumption per horsepower is high compared with modern turbines using higher steam pressures and temperatures. It is, therefore, a prime objective of this invention to provide new steam cylinders to replace existing steam cylinders of any conventional arrangement, such as 2 or 4-cylinder compound engines, 3 or 4-cylinder triple-expansion engines, and 4 or 5-cylinder quadruple-expansion engines, and which can be adapted to any number of cranks with any crank relationship, and which can safely be lubricated with steam of higher superheat and temperature, and pressures, when available, and which will reduce the steam and fuel consumption of the main engine as much as 30 to 40%.

With such a conversion, only the main cylin-

2

ders are replaced, and the new cylinders are built to fit existing columns, frames and bases, using these parts intact, together with the existing crankshaft, connecting rods and cross-heads, and using the existing conventional Stephenson linkage valve gear and the existing reversing jack and controls to actuate, by means of rocking cams, the poppet valves mounted in the cylinder heads of the new cylinder assemblies.

Old boilers may be utilized at their existing steam pressure with my novel cylinders by adding superheaters thereto to raise the steam temperature to 750–800° F. or more, thereby greatly reducing the steam and fuel consumption. In some cases of older ships, where the boilers need replacement and a reboiling job is under consideration, new boilers are installed, which will generate the steam at higher pressure, which together with the higher temperatures, results in additional economies.

Thus, many ships which still have serviceable hulls, but with main engines of obsolete design and which operate with a high fuel consumption, can be converted with my novel steam cylinders and with boiler superheaters, to reduce the fuel consumption to an amount where they can be profitably continued in service and in competition with modern turbine-propelled ships and other means of ship propulsion.

It is also practical and possible, with this design, to increase the horsepower output of the old engines up to the limit allowed by insurance authorities on the crankshaft and the propeller driving shaft, which results in increased speed of the ship. The increased speed gives additional mileage, with increased revenues for freight and passenger transportation. This, in many cases, is of more value than the fuel saving.

This design is not limited to conversion installations, but obviously can also be used on complete new ships and engines with more modern enclosed force-feed lubricated crankcases. It obviously also can be used for stationary installations for power purposes, with the same improvements in steam and fuel economies.

It is, accordingly, an object of my invention to overcome the above and other limitations in existing steam engines, and it is more particularly the object of my invention to provide a multi-cylinder, steeple-compound, reversing, poppet-valve steam engine which is simple in construction, efficient in operation and economical to manufacture.

Another object of my invention is to provide a

multi-cylinder steam engine with uniflow high pressure and uniflow low pressure cylinders.

Another object of my invention is to provide a steeple-compound uniflow steam engine which requires a minimum of head room.

Another object of my invention is to provide novel cooling means for the walls of the high-pressure cylinders of a steam engine.

Another object of my invention is to provide a compound steam engine operating with high steam temperatures, but with comparatively lower high pressure cylinder wall temperatures, and which can be safely and sparingly lubricated.

Another object of my invention is to relieve cylinder lubrication difficulties in a steam engine operating with high-temperature steam.

Another object of my invention is to provide a novel poppet-valve mechanism for a steam engine with variable cutoff and other steam events desirable for maximum economy and with proper maneuverability.

Another object of my invention is to provide a steeple-compound engine in which the high-temperature steam does not contact that portion of the piston rod which enters the crankcase.

Another object of my invention is to provide a multi-cylinder steeple-compound engine, in which the reciprocating parts of all cylinders are identical and interchangeable and of equal reciprocating weights, and in which the cylinders themselves are interchangeable duplicates, thereby reducing the number of spares which need to be carried and equalizing the reciprocating inertias, resulting in very much improved and smoother operation.

Another object of my invention is to provide a compound multi-cylinder steam engine which may be adapted for use with any number of cranks and in which a complete steam cycle is carried through on each crank.

Another object of my invention is to provide high-pressure cylinders in a compound multi-cylinder steam engine wherein exhaust steam issuing from the high-pressure cylinder to the low-pressure cylinder is utilized to cool the cylinder wall of the high-pressure cylinder, thus permitting the use of much higher initial steam temperatures.

Another object of my invention is to provide a steeple-compound engine in which both the high pressure and the low-pressure cylinders operate on the uniflow cycle, with attendant improved steam economies.

Another object of my invention is to utilize exhaust to cool the cylinder liners and walls of the high-pressure cylinder while passing the steam to the low-pressure cylinder, and to utilize the heat so absorbed in the steam to give useful work in the low-pressure cylinder.

Another object of my invention is to provide simple means, in a steeple-compound engine, where the lower cylinder is conventionally inaccessible, for inspecting the condition of the lower or low-pressure cylinder walls and piston rings without dismantling, and to make the low pressure piston packing rings replaceable through a removable bottom cover and without disturbing any other part of the engine.

Another object of my invention is to provide a steeple-compound uniflow engine which is operable on high-pressure and high-temperature steam conventionally used only in steam turbine practice.

Another object of my invention is to provide novel means for cooling the piston rod packing

disposed around the piston rod between the high-pressure and low-pressure cylinders in a steeple-type compound steam engine with the lower temperature steam used in the low-pressure cylinder.

Another object of my invention is to provide novel multi-steeple-compound cylinders with pistons and cylinder heads and poppet-valves and inlet and exhaust manifolds, which may be adapted to and mounted on conventional open frames or columns now in use, and which will utilize the existing cranks, connecting rods, cross-heads, bedplate with main bearings and shafting, and the conventional eccentric valve gearing, reversing mechanisms, etc., already assembled and in use on existing ships.

Another object of my invention is to provide novel multi-steeple-compound steam cylinders with a poppet-valve gear which can be actuated from existing conventional eccentrics and reversing mechanisms.

Another object of my invention is to minimize the horizontal distance between adjacent cylinder centerlines, which is governed by the diameter of the low-pressure cylinder, and thus gives a maximum total low-pressure piston area for a given centerline-to-centerline dimension on existing engines. This is accomplished in a single-acting high-pressure piston working with the pressure on the underside of the piston on the upstroke, and a single-acting low-pressure piston working with the pressure on its upper side on the downstroke, and by utilizing the upper side of the high-pressure piston to complement the low-pressure piston, both working on the downstroke.

Another object of my invention is to vent the underside of the low-pressure piston continuously to the condenser, maintaining the low temperature of the vacuum steam throughout most of the low-pressure cylinder. Thus, the low-pressure cylinders can be bolted together and to the columns of an open-frame engine, giving a rigid frame construction over the tops of the columns, desirable for rigidity, and with a minimum change in center-to-center horizontal dimension due to expansion, which is important to maintain alignment with the crosshead guides and cranks. At the same time, all adjacent low-pressure cylinders bolted together operate at very nearly identical temperatures, and expand vertically small and equal amounts.

In conventional open-frame compound triple- and quadruple-expansion steam engines, with double-acting cylinders, the high-pressure cylinder is much hotter than its adjacent intermediate pressure or low-pressure cylinder and to which it is bolted, and expands a great deal more, both horizontally and vertically. This results in severe stresses and much misalignment, which, due to this, further limits the steam temperatures which can be utilized on conventional engines. With my invention, the horizontal dimension expands only that amount due to vacuum temperature, 100-125° F., and these dimensions are not affected in any way by the initial steam temperature.

Another object of my invention is to keep the reciprocating weights on all cranks equal, thus minimizing vibration and weaving of the columns, the bedplate and the cylinders, which is a serious objection to all conventional compound triple- and quadruple-expansion engines where the weight of the low pressure piston far exceeds the weight of the high-pressure and intermediate-pressure pistons.

Another object of my invention is to increase the displacement of the low-pressure cylinders, which governs the referred low-pressure mean effective pressure in the cylinder. The greater the displacement, the lower the mean effective pressure for a given horsepower and speed, and the lower the mean effective pressure, the lower the steam rate per horsepower. To illustrate, where the three cylinders of a conventional triple-expansion engine are replaced, the original engine has one double-acting low-pressure cylinder, and in my invention it would have three single-acting low-pressure cylinders of approximately 50% increase in displacement. This further improves the economy, or it can be utilized to increase the horsepower output and speed of an old ship.

Other objects of my invention will become evident from the following detailed description, taken in conjunction with the accompanying drawings, in which:

Fig. 1 is a side elevational view of my novel compound uniflow steam cylinders mounted on the columns of a conventional triple-expansion marine engine and utilizing the eccentric valve gears of a triple-expansion steam engine to operate the poppet-valve gear of my novel steam cylinders;

Fig. 2 is an end elevational view of my novel steam engine shown in Fig. 1;

Fig. 3 is a top plan view of my novel steam engine shown in Fig. 1;

Fig. 4 is a sectional view taken on the line 4—4 of Fig. 3;

Fig. 4-a is a bottom view of the piston in the low pressure cylinder of my novel steam engine;

Fig. 5 is a fragmentary view showing the packing box engaging the piston rod disposed between the high-pressure cylinder and the low-pressure cylinder of my novel steam engine;

Fig. 6 is a sectional elevational view taken on the line 6—6 of Fig. 3;

Fig. 7 is a bottom view of the split end plates forming the lower covers of the low-pressure cylinders shown in Fig. 6;

Fig. 8 is a view taken on the line 8—8 of Fig. 6 with certain parts broken away for better illustration; and

Fig. 9 is a fragmentary vertical sectional view taken on the line 9—9 of Fig. 2.

For purposes of illustration, I have shown my novel steam cylinders, cylinder heads and valve operating mechanisms mounted on conventional vertical marine triple-expansion engine columns, although it will be evident that my novel cylinders, cylinder heads, manifolds and valve operating mechanisms may be mounted on any type of conventional frame or column with any number of cranks.

Referring now to the drawings, Figs. 1 to 11, inclusive, show a bedplate 1, front columns 2, back or guide columns 2a, guide members 3, low-pressure cylinders 4, high-pressure cylinders 5, a crankshaft 6 journaled in bedplate 1, and connecting rods 7. Since each pair of high and low-pressure cylinders 5 and 4 constitute a complete compound engine or power unit, I will describe only one power unit. A piston rod 12 has fixed thereon a high-pressure piston 13, operable in the high-pressure cylinder 5, and a low-pressure piston 15, operable in the low-pressure cylinder 4, and is pivotably connected to the connecting rod 7 by a crosshead 14 and a pin 11. The piston rod 12 extends through an aperture 16 in cylinder head 10 (Fig. 5), intermediate the high-pressure cylinder 5 and the low-pressure cylinder 4, and

passes through a flanged packing box 17 extending into aperture 16 and spaced from the sides thereof, in order that the packing box 17 will be insulated from the high-temperature steam in the cylinder head 10 and will be cooled by the low-temperature steam in the low-pressure cylinder 4. As shown particularly in Figs. 4 and 6, the low-pressure cylinder 4 comprises a cylindrical member 20 with exhaust ports 21 and an inwardly flanged portion 22, to which is attached split semi-circular plates 23, as shown in Fig. 7, by means of screw bolts 24. The flanged plates 23 have complementary depending flanged portions 25, which are secured together by bolt and nut assemblies 26, or by any other suitable means. When the flanged plates 23 are secured together, an apertured portion 27 is formed centrally thereof to receive the piston rod 12 and a flanged packing box 28. It will be evident that entrance to the lower end of the low-pressure cylinder 4 may be attained at any time by merely removing the plates 23.

The low-pressure piston 15 has an inverted L-shaped groove formed on the lower outer periphery thereof for nesting L-shaped rings 103 and packing rings 104 for sealing engagement with the inner wall of the cylinder 4. Segmental guide members 100 having soft-wearing metal pieces 101 are bolted to the underside of the piston 15 by means of capscrews 102 to secure the L-shaped rings 103 and packing rings 104 in the groove in the piston 15. By removing the capscrews 102 and segmental members 100, the L-shaped rings 103 may be dropped onto the flange 22 in the cylinder 4 and the packing rings 104 then may be renewed through the open bottom end of the cylinder 4 after the plates 23 are removed.

In addition, inspection ports 105 are cast in the low-pressure cylinder 4, opposite the ports 21, and these are covered with a removable plate 106 on the outside. By removing the plate 106 and by turning over the engine, the rings 104 will pass over these ports for inspection, and, at the same time, the entire interior of the low-pressure cylinder 4 is visible for inspection through these ports 105 with no dismantling of the engine.

An exhaust chamber 29 is formed on the periphery of the cylinder 4 outside of the exhaust ports 21, and to this a suitable flanged exhaust piping 30 is connected, leading to a condenser 31. Base portion 32 of the cylinder 4 is flanged and seats on the upper ends of the column members 2 and 2a.

The cylinder head 10 is secured to the upper end of the low-pressure cylinder 4, and has mounted on the upper side thereof and secured thereto, an inner sleeve 35, flanged outwardly at the bottom end thereof at 36, and an outer wall 37, spaced from the inner sleeve 35 to form the high pressure cylinder 5. The inner surface of the sleeve 35 is preferably electro-porous chrome-plated to give a hard smooth surface on which the packing rings of high-pressure piston 13 may ride with a minimum friction.

The inner sleeve 35 has exhaust ports 38 circumferentially thereof and spaced from the top end thereof by a distance equal to the vertical height of the high-pressure piston 13, and which give an initial uniflow exhaust of the steam in the high-pressure cylinder 5 and under piston 13 at the very top end of the stroke. This exhausted steam flows through the ports 38 into the annular chamber between the sleeve 35 and the out-

er wall 37 of the high-pressure cylinder 5, and from thence onto the top of piston 13, thus equalizing the pressures under and over the piston 13.

The outer wall 37 is flanged outwardly at 39 to receive a flanged domed head 40, which closes the upper end of the high-pressure cylinder 5. The outer wall 37 is flared outwardly intermediate thereof at 42, to form a steam chamber, and this is connected to steam line 43, which in turn is connected to an open passage 44 in the cylinder head 10, which leads directly to the upper end of the low-pressure cylinder 4. It will thus be seen that the steam freely passes from the high-pressure cylinder 5 to the top of low-pressure piston 15 and the top of high-pressure piston 13 when they are both at the top of their stroke.

A high-pressure steam line 45, connected with a manifold 51, is secured to the top surface of the cylinder head 10 diametrically opposite to the steam line 43 and connects with a steam chamber 46, the steam thereby passing from the chamber 46 upon opening of the poppet-valve 47 into port 47a, which is open to the high-pressure cylinder 4. Exhaust from the high-pressure cylinder 4 is continued after the pistons 13 and 15 recede from the top of their stroke by opening poppet valve 48, which connects the port chamber 47a, open to the high-pressure cylinder 5, with a steam passage 50 leading to the upper end of low-pressure cylinder 4. Poppet-valve 52 is provided in the cylinder head 10 to exhaust steam on the upstroke of low-pressure piston 15 from passage 44, which is open to the upper end of low-pressure cylinder 4, to a steam chamber 53, which passes the exhaust steam outwardly through passage 54 and exhaust line 55, on some cylinders directly to the exhaust line 39 leading to the condenser 31. On other cylinders, exhaust line 55 is connected to an exhaust manifold 56, which in turn is connected by extensions 57 and flanged joint 58 to aperture 59, opening into low-pressure cylinder 4 under the low-pressure piston 15, and from thence through ports 21 into manifold 30 leading to condenser 31.

In controlling the steam events in my novel steam engine, I utilize existing conventional eccentrics 60 on the crankshaft 6, having eccentric rods 61 leading to conventional links 62, which in turn are connected to valve rod 63, pivoted rocker arm 64, and adjustable link rod 65. In some cases, the eccentric motion is carried by a rocker arm 110 to a rock shaft 111 to another rocker 112, to which is pivotably connected adjustable link rod 65.

The valve rod 65 is pivotably connected to a double-armed rocker 66, which is adjustably mounted on a transversely extending camshaft 67, passing into camboxes 120 and 120a mounted on low pressure cylinder 4 on both sides of rocker 66. Each end of the camshaft 67 oscillates in flanged supporting bearings 121 bolted to the outer faces of camboxes 120 and 120a. The rocker 66 carries two circular faces 122 concentric with shaft 67, and are adjustably bolted to flanges 123 and 123a of sleeves 124 and 124a disposed about the camshaft 67, and which extend into camboxes 120 and 120a through packing glands 125.

The valve rod 65 through armed rocker 66 and suitable cams in camboxes 120 and 120a actuates the rocker arm 74. The upper end 76 of rocker arm 74 engages, by means of tappet screw 77 secured by nut 77a, the valve stem 78

of poppet-valve 47 to reciprocate and open and close this valve mounted in the flanged cage 79.

To the end of sleeve 124, within the cambox 120 (Fig. 4), is bolted a cam hub 81 concentric with and adjustable on camshaft 67, and has secured thereon by screw bolt 85 a cam member 82 having a key portion 83, which engages a slotted portion 84 in the side of cam hub 81. The rocker 86 is pivoted on shaft 75 and carries a cam roller 87 at its lower end, engaging the cam member 82. The upper end 88 of the rocker arm 86 engages, by means of tappet screw 88a and secured by nut 88b, valve stem 89 of the large exhaust poppet-valve 48, and reciprocates and opens and closes it in the flanged cage 91 in which it is supported.

With reciprocation of valve rod 65 upwardly, cam member 82 in cambox 120 will engage roller 87 of rocker 86, on whose upper end tappet screw 88a will engage valve stem 89, opening valve 48. With reciprocation of valve rod 65 downwardly, valve 48 will be closed and valve 47 will be opened.

The upper end of rocker arm 94 engages, by means of tappet screw 95 secured by nut 95a, a valve stem 96 of poppet valve 52 mounted in flanged cage 52a.

When poppet valves 47 and 52 are opened, the former serves to admit steam under the high-pressure piston 13 on the upstroke and the latter to exhaust steam from the low-pressure cylinder 5 above the low-pressure piston 15, which will also be on its upstroke. The lift on exhaust valve 52 will be less than that on admission valve 47, due to the short lever arm on rocker 94 as compared with the long lever arm on rocker 74.

The exhaust valve 52 may be manually lifted independent of admission valve 47 for the purpose of venting the low-pressure cylinder 5 continuously to the condenser for easy starting.

By proper disposition of the cam hubs and cam members in the camboxes 120 and 120a by means of coupling flanges 123 and 123a, and by proper proportioning of rockers 66 with the movement of the eccentric valve gear, proper steam events in the high and low-pressure cylinders 5 and 4 may be obtained. Furthermore, any system of eccentrics or any other type of conventional reciprocating valve gear may be adapted for use with my novel valve mechanism, although I have only shown the adaptation to the use of the conventional Stephenson eccentrics and links of a conventional triple-expansion steam engine with my novel valve mechanism. All valves and the mechanisms therefor are independently adjustable, therefore providing for maximum efficiency.

In operation, high-pressure steam from the steam manifold 51 passes through steam lines 45 to the steam chamber 46 in cylinder head 10 and from thence through the poppet-valve 47 to the high-pressure cylinder 5. This high-pressure steam acts upwardly on the underside of piston 13 in the high-pressure cylinder 5, and the steam is cut off at any suitable predetermined point by proper adjustment of the cam hub 68 and cam member 69 controlling the poppet-valve 47. When the piston 13 passes above the exhaust ports 38, steam passes outwardly between the inner sleeve 35 and the outer wall 37 and equalizes the pressure in the high-pressure cylinder with the pressure on top of the high-pressure piston 13 and in the annular space between sleeve 35 and outer wall 37 and through steam line 43 and passage 44 and with the steam on top of low-pressure piston 15. Immediately after starting the downward stroke, the ports 38 are again closed by pis-

ton 13, but by this time the exhaust poppet-valve 48 is open, thereby continuing the exhaust from the high-pressure cylinder 5 through this valve into the low-pressure cylinder 4. This cylinder is permanently open through passages 44, steam line 43, and the annular space between liner 35 and outer wall 37 to the top of the high-pressure piston 13. Both high-pressure piston 13 and low-pressure piston 15 then continue the downward stroke, and when they have reached a predetermined portion of their stroke, the exhaust poppet-valve 48 is closed. The piston 15 in the low-pressure cylinder 4, as it approaches the bottom of the stroke, opens exhaust ports 21 and exhausts all of the steam, both in low-pressure cylinder 4 and on top of high-pressure piston 13 in high-pressure cylinder 5, to the exhaust line 30 and to the condenser 31. Thus it is apparent that the top of piston 13 in high-pressure cylinder 5 serves to give an additional low-pressure displacement complementing that of the main low-pressure piston 15. The low-pressure piston 15, after reaching the bottom of its stroke, begins its upward stroke, and at a predetermined point in this upward movement, the low-pressure exhaust valve 52 is opened, continuing the exhaust to the condenser through exhaust lines 55 and 56 to the exhaust manifold 30 and the condenser 31. It will be evident upon inspection that proper movements and control of the poppet-valves 47, 48 and 52 may be obtained by proper design of the cam members 69 and 82 and proper positioning relative to the rocker arm 66.

It will be evident from the foregoing that I have provided a novel multi-cylinder steam engine which may be utilized to convert any present uneconomical, inefficient steam engine into one which can efficiently utilize high steam pressures and temperatures now prevailing in modern steam practice. By permitting the low-temperature steam of the low-pressure cycle to pass freely on top of piston 13 within the sleeve 35 and also between the sleeve 35 and the outer wall 37, this serves to keep the temperature of the sleeve 35 in the high-pressure cylinder 5 close to low-pressure cycle temperatures, and this temperature will be much below the initial high-temperature steam.

Also, the packing box 17 surrounding the piston rod 12 between the high-pressure and low-pressure cylinders 5 and 4 is steam cooled by low-pressure cycle steam within the low-pressure cylinder 4, thereby maintaining the temperature of the packing box 17 at the temperature of low-pressure steam and insulating it from the high-temperature steam within the cylinder head 10. The steam events in my novel steam cylinders are properly taken care of by the novel valve and cam arrangements which I have provided, and which may be adapted for use with any conventional bedplate and columns now in use with conventional eccentrics or any other type of conventional reciprocating valve gear. The same patterns may be used for all high-pressure cylinders and for all low-pressure cylinders, and all the cylinder heads therebetween, thereby greatly reducing the cost of manufacture.

My novel cylinder head and valve gear mechanism give accurate steam control throughout the entire range of ahead and astern cutoff adjustments, provides ample port areas, automatic pressure release, and it permits the efficient use in a steam engine of high-pressure and high-temperature steam used in modern steam practice.

I have further provided a multiple-cylinder steam engine wherein there is a direct and uninterrupted expansion of the steam from the cutoff point on the high-pressure upstroke to the uniflow exhaust on the low-pressure downstroke. The uniflow cycle used in both the high-pressure and low-pressure cylinders provides an efficient exhaust for handling instantly large steam volumes. Passing of the exhaust steam through the cylinder head between the high-pressure and low-pressure cylinders, which contains steam of high initial temperature, is thermally favorable on account of the reheating effect on the steam entering the low-pressure cylinder. The same thermally favorable effect is obtained by the heat removed from the high-pressure sleeve 35, and which is utilized in the low-pressure cycle. Both cylinder barrels are comparatively simple castings and simple to machine, which makes them quite different from the complicated cylinders and heads in conventional double-acting engines, particularly of the multiple expansion type.

Due to the use of a short piston in both the high-pressure and low-pressure cylinders, together with a single cylinder head placed between the two cylinders and serving both, the height or head room required for my novel steam cylinders is only approximately 10% more than that required by a double-acting uniflow engine of equal stroke, with its long piston and long cylinder and two cylinder heads, one above and one below.

With my novel engine, each pair of high pressure and low-pressure cylinders constitutes a complete compound engine and can, therefore, be built in any number of double cylinders and can accommodate any crank relations and gives balanced reciprocating weights. This differs from the conventional double-acting compound triple or quadruple-expansion engine. The compound must be built with 2 or 4 cylinders, the triple-expansion engine with 3 or 4 cylinders, and the quadruple-expansion engine with 4 or 5 cylinders. In each case the crank relations are more or less fixed and the diameters are different on each crank, resulting in unbalanced weights. They also require the development of several different sizes of cylinder bores, all of which can be accomplished with one development on my novel engine by varying the number of cylinders.

Valve operating mechanism for my novel multiple expansion steam engine is more particularly shown in my copending application for patent, Serial No. 28,612.

Various changes may be made in the specific embodiment of my invention, without departing from the spirit thereof, or from the scope of the appended claims.

What I claim is:

1. In a multi-cylinder steam engine, in combination, a high-pressure cylinder and a low-pressure cylinder having admission and exhaust ports, valves for controlling the steam events in said cylinders, and an open auxiliary steam line between said high-pressure cylinder and said low-pressure cylinder.
2. In a multiple-cylinder steam engine, in combination, a high-pressure cylinder with double walls, a low pressure cylinder, valves for controlling the steam events in said cylinders, and an open steam line between said low-pressure cylinder and the opening between the walls of said high-pressure cylinder.

3. A multiple-cylinder steam engine as set forth in claim 2 wherein said double wall in said high-pressure cylinder is open at the head end.

4. A multiple-cylinder steam engine as set forth in claim 2 wherein said double wall, high pressure cylinder has exhaust ports in the inner wall thereof.

5. In a multi-cylinder steam engine, in combination, a high-pressure cylinder and a low-pressure cylinder, said high-pressure cylinder having an inner sleeve spaced from the outer wall thereof, a cylinder head disposed between said high-pressure cylinder and said low-pressure cylinder having an open passage connecting the upper end of said low-pressure cylinder and the space between the wall and sleeve of said high-pressure cylinder, and valves in said cylinder head for controlling the steam events in said cylinders.

6. A multi-cylinder steam engine as set forth in claim 5 wherein the space between said inner sleeve and outer wall is open at the head end of the high-pressure cylinder.

7. A multi-cylinder steam engine as set forth in claim 5 wherein a portion of the outer wall of said high-pressure cylinder is flared outwardly to form a steam chamber between said inner sleeve and said outer wall.

8. In a multi-cylinder steam engine, in combination, a high-pressure cylinder having inner and outer walls, a low pressure cylinder, a cylinder head between said high pressure and said low-pressure cylinder having a passageway connecting the space between walls of said high-pressure cylinder with said low pressure cylinder, valves in said cylinder head, and means for actuating said valves to control the steam events in said high-pressure and said low-pressure cylinders.

9. In a multiple cylinder steam engine as set forth in claim 8 wherein a piston rod in said cylinders is surrounded by a packing in said cylinder head cooled by the steam in said low-pressure cylinder.

10. A multi-cylinder steeple compound engine comprising a high-pressure cylinder, an inner sleeve in said high-pressure cylinder spaced from the outer wall thereof having circumferentially disposed apertures therein, a low-pressure cylinder of the single-acting uniflow type disposed below said high-pressure cylinder, a cylinder head disposed between said high-pressure and said low-pressure cylinder having passages for admitting steam to said high-pressure cylinder, for exhausting steam from said high-pressure cylinder to said low-pressure cylinder, and an open passage connecting the chamber between said sleeve in said high-pressure cylinder and the outer wall thereof and the top of said low-pressure cylinder, valves in said cylinder head for opening and closing said admission and exhaust passages in said cylinder head, and means for controlling said valves to control the steam events in said cylinders.

11. A multi-cylinder steeple compound engine as set forth in claim 10 wherein an exhaust valve and passage is provided in said cylinder head to exhaust steam from said low-pressure cylinder.

12. A multi-cylinder steeple-compound engine as set forth in claim 10 wherein said low-pressure cylinder has inspection ports in the side walls thereof.

13. A multi-cylinder steeple compound engine comprising a high-pressure cylinder of the uniflow type having an inner apertured sleeve spaced from the outer wall thereof, a low-pressure cylinder

der, a cylinder head disposed between said high-pressure cylinder and said low-pressure cylinder having an open passage, a steam line connecting the area between the inner sleeve and outer wall of said high pressure cylinder, said open passage and said low-pressure cylinder for passage of steam therebetween, and means for controlling the steam events in said cylinders.

14. A multi-cylinder steeple compound engine comprising a high-pressure cylinder, a sleeve in said high-pressure cylinder having circumferentially spaced ports therein and spaced from the top of said cylinder, and from the outer wall of said cylinder, a low pressure cylinder of the uniflow type, a cylinder head having an open passage disposed between said high-pressure and said low-pressure cylinder, a steam line connecting the space between the inner sleeve and the outer wall of said high-pressure cylinder, said open passage in said cylinder head, and said low-pressure cylinder, and means for controlling the steam events in said cylinders.

15. A multi-cylinder steeple compound engine comprising a high-pressure cylinder of the uniflow type having spaced walls, the inner wall being spaced from the top of said cylinder, a low pressure cylinder of the single-acting uniflow type, a cylinder head having an open passage and admission and exhaust ports disposed between said high-pressure and said low-pressure cylinder, a steam line for connecting the space between the walls of said high pressure cylinder, said open passage in said cylinder head, and said low-pressure cylinder, valves in said cylinder heads for controlling the admission of steam to said high-pressure cylinder and exhaust steam from said high-pressure cylinder to said low-pressure cylinder, and means for actuating said valves to control the steam events in said cylinder.

16. A multi-cylinder steeple compound engine as set forth in claim 15 wherein an exhaust valve is disposed in said cylinder head for exhausting steam from said low-pressure cylinder.

17. A multi-cylinder steeple compound engine comprising a plurality of high-pressure cylinders of the uniflow type, a plurality of low-pressure cylinders of the uniflow type, cylinder heads between said high-pressure cylinders and said low-pressure cylinders having admission and exhaust ports, and an open passage, steam lines for connecting the high-pressure cylinders to said open passages in said cylinder heads and said low-pressure cylinders, admission valves and exhaust valves for controlling the admission and exhaust ports in said cylinder heads, exhaust valves for said low-pressure cylinders disposed in said cylinder heads, means for actuating said valves to control the steam events in said cylinders, and selective means for actuating said exhaust valves for said low pressure cylinders.

18. A multi-cylinder steam engine comprising a double walled high-pressure cylinder of the uniflow type, a low-pressure cylinder of the uniflow type, valves for controlling the steam events in said cylinders, and an open steam line between the chamber formed between the walls of said high-pressure cylinder and said low-pressure cylinder.

19. A multi-cylinder steam engine as set forth in claim 18 wherein the inner wall of said high-pressure cylinder comprises an inner sleeve spaced from the side and top of the outer wall thereof.

20. A multi-cylinder steam engine comprising

a high-pressure cylinder, a low-pressure cylinder, a piston rod extending through said cylinders, pistons fixed on said rod in said high-pressure cylinder and said low-pressure cylinder, and an open steam line connecting said high-pressure cylinder and said low-pressure cylinder and valves for controlling the steam events in said cylinder.

HERMAN G. MUELLER.
